UNITED STATES PATENT OFFICE.

FRIEDRICH WILHELM SCHUBERT, OF APPERLEY BRIDGE, NEAR BRADFORD, ENGLAND, ASSIGNOR TO BRYSLKA, LIMITED, OF APPERLEY BRIDGE, NEAR BRADFORD, ENGLAND.

COLLAPSIBLE REEL FOR WINDING FILAMENTS, YARNS, THREADS, SILKS, AND THE LIKE.

Application filed June 21, 1926, Serial No. 117,538, and in Great Britain July 2, 1925.

This invention relates to collapsible reels for winding filaments, yarns, threads, silks and the like, (hereinafter termed filaments), the chief object being to provide a reel wherein the supporting surface or surfaces may be moved directly and instantaneously out of contact with the filaments during the action of collapsing for the purpose of removing said filaments. In a previously proposed collapsible skeining or winding cylinder the skein supporting surface comprises collapsible peripheral segments pivotally connected to fixed segmental members, means being provided for collapsing the pivoted segments inwardly toward the centre.

According to the present invention, the filament supporting surface or surfaces of the reel comprise three segmental portions, two of which are pivotally connected to the third and adjustably secured to each other, means being provided for locking the segments in the extended or erected position.

In order that the invention may be clearly understood and readily carried into effect, the same will now be more fully described, with reference to and by aid of the accompanying drawings; wherein:

Figures 1, 2 and 3 are respectively a side elevation, half sectional plan and a detail view illustrating a collapsible reel according to the invention.

Referring to the drawings, the reel comprises a central shaft 1, on which is fixed a segmental portion 29, having pivotally connected thereto at the points 30, a pair of segmental portions 31, said segmental portions

29, 31, being provided with transverse ebonite or other bars 8, constituting the filament supporting surface. The segmental portion 40 29, is provided with a radial arm 32, carrying at its outer extremity a cross member 33, adapted through the medium of catches 34, to hold the two segments 31, in the outer or filament supporting position. The member 33 is provided with a press button or plunger 35, adapted, when depressed against the action of a provided spring 36, to disengage the catches 34, and permit of the segments 31, being collapsed or moved about 45 their pivotal points 30, towards the centre, so as to permit of the ready removal of the filament from the supporting bars 8.

I claim:

1. Collapsible reels for winding filaments, 55 yarns, threads, silks and the like, wherein the filament supporting surface or surfaces comprise three segmental portions, two of which are pivotally connected to the third and adjustably secured to each other, means 60 being provided for locking the segments in the extended or erected position.

2. Collapsible reels for winding filaments, 65 yarns, threads, silks and the like, according to claim 1, wherein the segments are provided with transverse ebonite or other bars constituting the filament supporting surface, and in which the said third segment is provided with a radial arm carrying at its outer extremity a cross member adapted 70 through the medium of catches to hold the two pivoted segments in the outer or filament supporting position.

FRIEDRICH WILHELM SCHUBERT.
